COMBINED PORTABLE TELEPHONE ENCLOSURE AND SUPPORT

William E. Whidden, Chatham, N.J., assignor to Bell Telephone Laboratories, Incorporated, New York, N.Y., a corporation of New York

Filed Apr. 18, 1961, Ser. No. 64,807

Term of patent 14 years

(Cl. D26—14)

FIG. 3

FIG. 2

FIG. 1

FIG. 1 is a perspective view of a combined portable telephone enclosure and support, showing my new design;

FIG. 2 is a fragmentary perspective view showing the enclosure in open position; and

FIG. 3 is a fragmentary perspective view showing the enclosure in closed position.

The broken line disclosure is for illustrative purposes only.

I claim:

The ornamental design for a combined portable telephone enclosure and support, substantially as shown and described.
